PNEUMATIC DELIVERY BOX

Arthur Linnert and Gordon Short, Manchester, England

Application March 31, 1955, Serial No. 498,396

Claims priority, application Great Britain April 1, 1954

6 Claims. (Cl. 19—75)

This invention concerns pneumatic delivery boxes, and in particular pneumatic delivery boxes as used in the textile industry, in a pneumatic conveying system, for extracting fibrous material, especially cotton, from the conveying air to effect delivery at a required location.

Known delivery boxes embody a cylindrical cage, the periphery of which is perforated, and which in use is rotated in the path of the pneumatically conveyed fibrous material so that the material is collected on part of its periphery. A damper is provided within the cage to blank off another part of its periphery from the suction effect caused by the flow of air and the box has an outlet adjacent this blanked off part. In order to remove the material from the periphery of the cage and avoid any adverse effect due to the provision of the outlet opening in the box and consequent ingress of air therethrough a shrouded stripper roller has been used, or preferably an improved sealing arrangement has been employed.

It has also been proposed to use a rotating disk, having, at intervals, perforate portions separated by radial partitions secured to one face of the disk, to remove cotton and other fibers from an air-stream. The proposal comprises the mounting of the disk in a casing having inlet and outlet ports for the air-stream, and by rotation of the disk with its axis parallel to the flow, the bringing of the separate sections formed by the partitions successively into alignment with the flow and then out of the casing, to remove the fibers from the air stream.

It has furthermore been proposed to use a co-operating perforate disk and wiper similarly mounted in a casing through which the laden air passes, so that the interaction of the disk and wiper, when one of these is rotated, removes material deposited on the disk to a relatively dead space in the casing, subsequently to be removed therefrom by an additional device.

The object of the present invention is to provide a pneumatic delivery box of simplified construction, efficient performance, low cost, and which is easy to manufacture, assemble and maintain.

According to the present invention a pneumatic delivery box comprises a flat, circular, perforated disk, two aligned lengths of ducting, the adjacent ends of which are spaced apart sufficiently to allow the disk, which is mounted for rotation about an axis lying outside the ducting and parallel to the longitudinal axis thereof, to pass between them, sealing means between the ducting and the disk, part of which, on the one length, is displaceable under the influence of material collected on the corresponding face of the disk, to allow the material to be carried away out of the ducting to fall from the disk for collection, and means for driving the disk.

The invention will now be described further, by way of example, with reference to the accompanying drawings, in which,

Fig. 1 is a pneumatic delivery box constructed according to the invention and shown in elevation;

Fig. 2 is an end elevation from the right of Fig. 1;

5

2

Fig. 3 is a perspective view of the delivery box illustrated in Figs. 1 and 2 when in operation;

Fig. 4 is a detail view showing in elevation the quick-release arrangement for the disk, and

Fig. 5 is an end elevation from the left of Fig. 1.

The delivery box illustrated is intended in use to collect cotton fibers from an air stream by which they are being conveyed and deliver them to a desired location.

Basically the delivery box consists of two lengths of ducting 11, 12 mounted in end to end alignment in a pneumatic conveying system, and, between their adjacent ends, a motor driven perforated disk 13 mounted on a shaft 14 driven by a motor 15 through a right angle drive arrangement 16. The motor 15 and the drive arrangement 16 are supported from the ducting by suitable arms 17, 18, a bracket 19, and platform 20. The arms 17, 18 also serve to connect the lengths of ducting whereby the whole box is constructed as a unit. The lengths of ducting are circular in cross-section at their outer ends, and of the same size as that of the ducting of the pneumatic conveying system into which they are to be inserted, the connection of the box in the system being thereby facilitated.

The disk 13 has a plurality of small perforations accurately spaced for approximately 50% of its face area and is mounted for rotation about an axis parallel to the longitudinal axis of the ducting, the two lengths 11, 12 of which are spaced apart sufficiently to allow free movement of the disk 13 between them. The diameter of the disk 13 is about three times that of the basic diameter of the ducting and the longitudinal axis of the ducting is displaced from the axis of rotation of the disk by a distance equal to about half the radial extent of the disk.

The adjacent end regions of the lengths of ducting 11, 12 are gradually enlarged in the direction of rotation of the disk 13 up to about twice the basic cross-sectional area of the ducting until they almost abut identical areas of the respective faces of the disk 13. Adjacent the disk the edge or perimeter of the enlarged end region is defined each bounded by a radial edge line *a* extending from the disk center, by a semi-circle *b* of radius equal to the basic radius of the ducting, diameter *c* which lies radially of the disk, and by curves *d*, *e* which diverge slightly in the direction of rotation of the disk (shown by the arrow in Fig. 2) and connect the ends of the semi-circle with the opposite ends, respectively, of said radial edge.

Leather sealing strips 21, 22, 23 are attached to the edges of the enlarged ends of the lengths of ducting 11, 12 by clamping strips 25 and bolts 26 to prevent loss of air which would otherwise occur owing to the clearance between the ducting and the disk. The sealing strip 21 on the radial edge of the enlarged end of the length of ducting which conveys the air and cotton up to the disk is attached to a flap 27 which is hinged to the ducting 11 by a hinge 28. The hinge is arranged so that the member may be opened by pivoting it in the direction of rotation of the disk. The flap 27 is spring loaded in the direction of the disk 13 by virtue of an arm 29 attached thereto, which is under the influence of a tension spring 30. A pin 31 may be moved along a slot 32 to provide an adjustable stop for the arm 29.

The disk 13 (Figs. 4 and 5) has a metal boss 13a in which are two bayonet slots 13b. These slots are adapted to receive a pair of diametrically opposed pins 33 having enlarged heads which are mounted on a plate 34 fitted to the end of shaft 14. The center portion of each slot 13b is large enough to allow the head of each pin 33 to pass therethrough and when the disk 13 is then turned in the opposite direction to its direction of rotation it will be ready for use. This arrangement enables the disk 13 to be quickly positioned or removed. The sealing strips 21, 22, 23 are designed so that, with the

disk removed a seal is maintained by contact of the oppositely disposed strips.

It has been found desirable for the disk 13 to be a somewhat loose fit on its shaft 14 and on the pins 33 to allow, in use, for the fact that the disk may not be quite flat.

In use (Fig. 3) the delivery box is mounted horizontally as a unit in a conveyor system and the motor 15 switched on to drive the disk. The cotton C carried along into the box by the air stream is collected by the rotating disk as it passes between the adjacent ends of the lengths of ducting and is allowed to pass out of the box by the hinged member, which is usually, as in the example of the invention being described, horizontally disposed. Immediately the cotton is out of the box and no longer subject to the influence of the air flow, it falls off the disk to a collecting station.

The invention of course is not limited to the particular details of the preferred embodiment just described. For instance the drive to the disk, may instead of being as described, be via a central gear wheel on the disk, or be a friction drive to a rim or flange provided on the edge of the latter. Further, a useful modification is the provision of about four equi-spaced spoke-shaped wires soldered to that face of the disk facing the on-coming air stream, which are found to assist in the action of the delivery box when the amount of cotton being conveyed is small.

What we claim is:

1. A pneumatic delivery box comprising in combination a flat, circular, perforated disk, two aligned lengths of ducting, the adjacent ends of said lengths being spaced apart sufficiently to allow said disk, which is mounted for rotation about an axis lying outside the lengths of ducting and parallel to the longitudinal axis thereof, to pass between them, sealing means between each length of ducting and said disk, part of said sealing means on the one length being displaceable under the influence of material collected on the corresponding face of said disk to allow the material to be carried away and out of the ducting, to fall from the disk for collection, and means for driving the disk.

2. A pneumatic delivery box as set forth in claim 1 in which said part of said sealing means is mounted on a spring loaded hinged member whereby it is resiliently displaceable.

3. A pneumatic delivery box comprising in combination a flat, circular, perforated disk, two aligned lengths of ducting, an enlarged end on each said length of ducting, said ends being disposed adjacent each other to enable said disk to pass therebetween, a hinged member forming that edge of one of said lengths of ducting at which the surface of said disk when rotating passes from between said lengths of ducting, sealing means secured at all the edges of said ends, spring means for normally urging said hinged member against said disk, a shaft disposed outside said lengths of ducting and parallel to the longitudinal axis thereof, said disk being detachably secured to said shaft and means for driving said shaft to rotate the disk.

4. A pneumatic delivery box as set forth in claim 3 in which said sealing means consists of a leather strip.

5. A pneumatic delivery box comprising in combination a flat, circular, perforate disk, two like aligned lengths of ducting, of basically circular cross-section, a shaft disposed outside said lengths of ducting and parallel to the longitudinal axis thereof, said disk being attachably

secured to said shaft, means for driving said shaft to rotate said disk, an enlarged end on each said length of ducting of about double the basic cross-sectional area thereof, said ends being disposed adjacent each other to enable said disk to pass therebetween, and so as almost to abut identical areas of the respective faces of said disk, each enlarged end having its perimeter defined by a radial edge line extending from the center of said disk, by a semi-circle of radius equal to the basic radius of the ducting the diameter of which lies radially of the disk, and by curves diverging slightly in the direction of rotation of the disk and connecting the ends of said semi-circle with the opposite ends, respectively, of said radial edge, a hinged member forming said radial edge of one of said lengths of ducting at which the surface of said disk passes when rotating from between said lengths of ducting, sealing means secured at all the edges of said ends, and spring means for normally urging said hinged member against said disk.

6. A pneumatic delivery box comprising in combination a flat, circular, perforate disk, two like, aligned lengths of ducting of basically circular cross-section, connecting means for holding said lengths of ducting in alignment, a shaft disposed just outside said lengths of ducting and parallel to the longitudinal axis thereof, said disk being secured to said shaft, quick-release means for speedily detaching said disk from said shaft, a motor for driving said shaft to rotate said disk, a drive transmission between said motor and said shaft, support means of unitary construction with said connecting means, for said motor, said transmission and said shaft, an enlarged end on each said length of ducting at least double the basic cross-sectional area thereof, said ends being disposed adjacent each other to enable said disk to pass therebetween, and so as almost to abut identical areas of the respective faces of said disk, each enlarged end having its perimeter defined by a radial edge line extending from the center of said disk, by a semi-circle of radius equal to the basic radius of the ducting, the diameter of the semi-circle lying radially of the disk, and by curves diverging slightly in the direction of rotation of the disk and connecting the ends of said semi-circle with the opposite ends, respectively, of said radial edge, a hinged flap forming said radial edge of one of said lengths of ducting at which the surface of said disk passes when rotating from between said lengths of ducting, flexible sealing strips secured to all the edges of said ends, and spring means for normally urging said flap so that its sealing strip makes sealing contact with said disk surface but allows said flap to be resiliently displaced under the influence of material collected on the corresponding surface of said disk to allow the material to be carried away and out of the ducting, to fall from the disk for collection.
